UNITED STATES PATENT OFFICE.

JOHN KELLER AND RICHARD TITSWORTH, OF FORT BLISS, TEXAS.

APAREJO.

SPECIFICATION forming part of Letters Patent No. 692,859, dated February 11, 1902.

Application filed April 25, 1901. Serial No. 57,501. (No model.)

To all whom it may concern:

Be it known that we, JOHN KELLER and RICHARD TITSWORTH, citizens of the United States, stationed at and residing at Fort Bliss, 5 El Paso, in the county of El Paso and State of Texas, have invented certain new and useful Improvements in 'Aparejos; and we do hereby declare the following to be a full, clear, and exact description of the invention, such 10 as will enable others skilled in the art to which it appertains to make and use the same.

This invention aims to improve the pack-saddle or aparejo in use by the United States Army, whereby greater efficiency and durability are secured and the beast of burden made more comfortable and less liable to fatigue, since the pressure and load are uniformly distributed upon the animal, which is not bound as by a vise-like grip, which retarded arterial circulation and fatigues and detracts from the endurance and serviceability of the animal.

The invention deals more particularly with the means for stiffening the casing forming 25 the body of the aparejo; and it consists of a hollow boot-stick at each end of the casing, ribs of steel inclosed in tubes of rubber, textile, or any cushioning material and having their lower ends fitted in the boot-sticks and 30 their upper ends loose, and caps fitted to the ends of the ribs to properly space them. These features will be set forth more particularly hereinafter and specified in the appended claims and are illustrated in the drawings, in 35 which—

Figure 1 is a front elevation showing the stiffening means in dotted lines. Fig. 2 is a top plan view, the casing or body being extended and parts broken away. Fig. 3 is a 40 plan view of the inner side of the casing, parts broken away, on a larger scale. Fig. 4 is a perspective view of one of the ribs, showing the caps of the boot-stick. Fig. 5 is a perspective view of one of the caps.

Corresponding and like parts are referred to in the following description and indicated in all the views of the drawings by the same reference characters.

The casing comprising the body of the aparejo is composed of two sections of flexible material—as leather, duck, or the like—stitched or otherwise secured at or near their

edges and intermediate of their ends in the usual way and about on the lines indicated in the drawings. This casing is flexible and 55 is reinforced at its edges and ends by facings and is provided centrally of its front edge with the part 1, forming the collar. Flaps 2 project from the rear edge upon opposite sides of a central line for the attachment to the 60 aparejo of the crupper. (Not shown.) The outer section 3 of the casing is imperforate, whereas the inner section 4 is provided with openings 5 and a slot 6 for the introduction of the sticks, ribs, and filling material forming 65 the padding. In general outline the casing is of rectangular form, and the space between the sections is occupied by the stiffening devices and the filling.

Each side and end portion of the aparejo is 70 tacked and stiffened alike. Hence a detailed description of one only will be given. The boot-stick fitted in the lower end of each side is hollow and consists of a casing 7 of sheet-steel or other metal and a stiffener 8, the latter being preferably a wooden stick or bar fitted into the inner closed portion of the casing, so as to prevent longitudinal bending thereof. The upper or top side of the casing 7 is open to receive the lower ends of the ribs 80 9, by means of which the sides of the aparejo are stiffened in a direction at a right angle to the boot-sticks. The boot-sticks and the ribs are placed in position through the openings 5 and slots 6. The ribs 9 consist of steel rods 10, 85 incased in tubes 11, of rubber, textile, or other material suitable for the purpose. By having the rods 10 formed of steel they may be exceedingly light compared with their bracing action. The rods may be of brass or other material 90 capable of possessing a high resiliency. The tubes 11, incasing the metal spring-rods 10, serve simply to fill the space between the sections 3 and 4 of the casing or body of the aparejo. The ribs are spaced apart and are 95 protected at their ends by caps 12 and 13 of similar formation, the caps 12 being of metal and the caps 13 of rubber or analogous flexible and soft material. The caps may be single or connected in series, and in either 100 form of construction they are spaced apart the required distance according to the desired spacing between the ribs. The caps 12 are preferably of metal, so as to resist wear, and

are fitted in the space of the boot-stick or casing 7. The upper caps 13 are of rubber to prevent injurious pressure of the upper ends of the ribs on the back of the animal by affording a cushion for the upper ends of the ribs. The caps are spaced apart by longitudinal ribs or lugs 14 at opposite sides thereof. The lower ends of the ribs are connected in series by the boot-sticks, whereas their upper ends are free and adapted to conform readily to the shape of the animal, so as to uniformly distribute the weight and pressure upon the back and side of the animal, which is of material advantage both in point of endurance and comfort of the animal.

15 In assembling the parts the boot-sticks are first placed in position by insertion through the openings 5, after which the ribs with their ends capped are inserted through the slot 6 and properly arranged in the casing, with their lower ends fitted into the space of the boot-sticks. The filling is next placed in position through the openings 5, after which the aparejo is in condition for use in the manner 20 well understood.

25 Having thus described the invention, what is claimed as new is—

1. In an aparejo, and in combination with the flexible body or casing, boot-sticks located 30 in the ends of the casing, and ribs having their lower ends fitted to said boot-sticks and having their inner or upper ends loose and adapted to conform to the shape of the animal so as to uniformly distribute the pressure 35 and load, substantially as set forth.

2. In an aparejo, and in combination with the casing or body, boot-sticks located in the ends thereof, and ribs having detachable connection with the boot-sticks and loose at their 40 inner or upper ends, substantially as set forth.

3. In an aparejo, and in combination with the flexible casing or body, hollow boot-sticks located at the ends thereof, and ribs having their upper ends loose and their lower ends 45 fitted in the spaces of the boot-sticks, substantially as set forth.

4. In an aparejo, and in combination with

the casing or body, ribs located within the casing, means for confining the ribs, and caps fitted to the ends of the ribs and serving to 50 properly space them, substantially as set forth.

5. In an aparejo, and in combination with the casing or body, ribs located within the casing, means for confining the ribs, and caps 55 fitted to the ends of the ribs and having lugs at their sides to properly space the ribs, substantially as set forth.

6. In an aparejo, and in combination with the casing, hollow boot-sticks located at the 60 ends of the casing, caps applied to the boot-sticks and located in the spaces thereof, and ribs having their lower ends inserted in the said caps, substantially as set forth.

7. In an aparejo, and in combination with 65 the casing or body, boot-sticks located at the ends of the casing, ribs having their lower ends fitted to the boot-sticks, and caps of rubber or analogous soft and flexible material fitted to the upper ends of the ribs and serving to 70 properly space said ends and prevent injurious pressure thereof upon the animal, substantially as set forth.

8. In an aparejo, and in combination with the casing or body, boot-sticks located in the 75 ends of the casing and formed of metal casings and stiffeners, the latter occupying the inner or lower portion of said metal casings, metal caps inserted in the upper spaces of the metal casings, incased spring-metal rods having their lower ends inserted in said metal caps, and caps of rubber or like flexible and soft material fitted to the upper ends of the incased rods, said caps having lugs or projections at their sides to properly space the 80 incased rods, substantially as set forth.

In testimony whereof we affix our signatures in presence of two witnesses.
